FIG. 1.

FIG. 2.

FIG. 3.

INVENTOR
ROBERT R. WARE

By Cheever & Cox
ATTY'S

UNITED STATES PATENT OFFICE.

ROBERT R. WARE, OF CHICAGO, ILLINOIS.

ROLLER.

Application filed March 13, 1926. Serial No. 94,474.

My invention relates to rollers, particularly for roller skates, and is an improvement over the form shown in Patent No. 1,469,344 granted October 2nd, 1923 to 5 Walter Ware of Chicago. In the earlier type, in addition to the hub and tire, four principal members were employed, viz two side plates or bushings and two rings located on either side of the bushings and 10 adapted to clamp the bushings and the tire between them. One object of my invention is to simplify the prior construction and to produce a roller consisting of four principal parts in contrast to the six principal parts 15 which were required in the previous type. Another object is to provide a construction such as to simplify assembly of the parts and to produce a more accurate roller by avoiding the possibilities for inaccurate adjustments present in the previous construction. Another object is to eliminate the errors apt to arise in mass production due to 20 variations in configuration of the parts which my invention makes superfluous. 25 Still another object is to improve the rigidity of the structure by forming side plates which lend themselves to a crimping or indenting operation after the parts are assembled, to thereby tighten the tire to a 30 greater extent than is possible by ordinary rivets alone.

I accomplish my objects by the mechanism illustrated in the accompanying drawing, in which—

35 Figure 1 is a side view of a complete roller.

Figure 2 is an axial section thereof; and

40 Figure 3 is an axial section of the different component parts separated sufficiently to show their individual construction and at the same time indicate their relationship when assembled.

Like numerals denote like parts throughout the several views.

45 According to my invention the hub 1 has an annular race 2 for the anti-friction balls 4 in the known manner. The tire 6, which may be of vulcanized rubber or other suitable substance, has an internal dovetail 50 flange 8. These parts are the same as in the type previously known.

According to my invention, but two additional parts are principally required for completing the structure. These two parts

55 are identical in form and consist of side plates of pressed metal having peripheral

flanges 10 and central openings 12 of sufficient diameter to loosely accommodate the hub 1. Viewed from the inner side these plates have annular ribs 14 which bear 60 against each other and result in the formation of arches 16 which together constitute raceways for the balls. Thus the ribs act as spacers to hold the arches at the proper distance apart, and as spacers to hold the 65 flanges 10 at the proper distance apart. Thus it is a two-piece structure which forms the body of the roller, that is, the entire connection between the hub and the tire.

When assembled, the side plates are held 70 together by rivets 18 which pass through the peripheral flanges 10.

Ordinarily after assembling, the roller is placed in a press which makes annular depressions 20 in the flanges between rivets. 75 This not only causes the metal to sink into the tire flange but also presses the plate flanges tightly against the sides of the tire flange, and makes a very tight, rigid structure.

80 From the foregoing it will be seen that my roller consists of but four principal pieces—the hub, the tire and the two side plates. This results in several advantages over the type shown in the above mentioned 85 patent. In the first place only two pieces need be handled instead of four, and these two pieces are identically alike. In the second place the assemblage is greatly simplified for in the previous construction it was 90 necessary to bring all four of the parts together in a particular way so that they would interlock, and this not only consumed time but there was always a possibility that some of the parts would not be of true form 95 or would, when riveted together, be drawn out of proper position, thus making a roller which was not accurately true and symmetrical.

100 These possibilities for error are done away with in my structure for the chief thing necessary is to bring the two plates together with their ribs 14 contacting each other and, practically speaking, there is nothing to get out of true. It is something more than a question of mere convenience 105 for it makes possible production of a lighter, truer wheel at a reduced cost for both labor and material.

Having thus described my invention what I claim as new and desire to secure by Letters Patent is:

1. A ball bearing roller having a hub pro-

vided with a raceway for the balls, a tire having an internal circular flange, and two annular pressed metal side plates of identical form each having marginal flanges for 5 engaging the sides of the tire flange and circular ribs on the inner side forming internal arches which together constitute a raceway for the balls, the ribs being adapted to bear against each other to thereby space the 10 arches and the peripheral flanges which engage the tire flange.

2. A ball bearing roller having a hub provided with a raceway for the balls, a tire having an internal circular flange, and a 15 two-piece structure forming the connection

between the hub and the tire, the two pieces consisting of pressed metal annular plates of identical form each having a central opening for loosely accommodating the hub, a marginal flange for engaging the tire flange and 20 an internal rib, the ribs forming internal arches constituting raceways and contacting each other to thereby space the arches and the marginal flanges, and means passing through the marginal flanges for holding the 25 entire structure assembled.

In witness whereof, I have hereunto subscribed my name.

ROBERT R. WARE.
